UNITED STATES PATENT OFFICE.

PHILIP HENRY KELLS, OF ADRIAN, MICHIGAN.

BRICK-MACHINE.

SPECIFICATION forming part of Letters Patent No. 295,558, dated March 25, 1884.

Application filed October 18, 1883. (No model.)

To all whom it may concern:

Be it known that I, PHILIP H. KELLS, a citizen of the United States, residing at Adrian, in the county of Lenawee and State of Michigan, have invented a new and useful Brick-Machine, of which the following is a specification, reference being had to the accompanying drawings.

This invention has relation to brick-machines; and it consists in the construction and novel arrangement of parts, as will be herein-after fully described, and particularly pointed out in the claim appended.

In the drawings hereto annexed, Figure 1 is a perspective view of my improved brick-machine with the nose-piece detached, for the purpose of showing the construction more clearly. Fig. 2 is a side view. Fig. 3 is a top view. Fig. 4 is a longitudinal vertical sectional view on the line *xx* in Fig. 3. Fig. 5 is a transverse vertical sectional view on the line *yy* in Fig. 3.

The same letters refer to the same parts in all the figures.

In the drawings designates the base, which supports a frame, B, having bearings or boxes for the main driving-shaft C, which is provided at its rear end with a band-wheel, D, or other suitable means for receiving motion from any desired power. The frame B is provided with a semicircular flange, E, serving to support the front end of the lower half, F, of the tempering-chamber G. The latter, which is constructed, mainly, of the two halves or sections F and H, is of a tapering or conical shape, as shown. The sections F and H are provided with laterally-projecting flanges I J, united by screws or bolts K, and the flanges I of the lower section, F, are provided with lugs L, connected by bolts or rods M with the frame B, to which the said section F and the tempering-chamber are thus firmly secured. If desired, additional lugs and fastening-bolts may be provided without departing from the spirit of my invention. The front end of the tempering-chamber rests upon and may be suitably secured to a plate, N, mounted upon uprights O O and P at the front end of the base. The said plate has an opening, Q, registering with the mouth of the tempering-chamber, and provided with inclined flanges R R at its sides. To these flanges is secured

the inclined nose-piece or cover S, forming a tapering chamber, T, which I denominate the "pressure-box." 55

U is the mold-wheel, which is mounted to revolve in a horizontal plane upon the central axis or upright, P, as shown. The said mold-wheel consists of a disk of suitable proportions, the periphery of which is provided with teeth or cogs V, and the body of which is provided with radial slots W, which form the mold-boxes. The bottoms of the latter are provided with flanges X to retain the plungers Y, which are provided with downwardly-extending 60 bearings Z, carrying friction rollers or casters A'. The base A supports a cam-shaped or inclined track, B', that engages the friction-rollers of the plungers, so as to force the latter in an upward direction on the upward incline of 65 the track B' as the wheel revolves. The said track being located out of the line of the tempering and pressure chambers will allow the plungers to drop upon their flanges while they pass under the pressure-chamber from which the molds receive their charges of clay, in order that the molds may receive their charges of clay. The mold-wheel engages and is operated by a pinion, C', mounted upon a vertical shaft, D', which is journaled in suitable 70 boxes or bearings upon the base A and the plate N, as shown. Said shaft D' also carries a bevel-wheel, E', engaging a pinion, F', on the front end of the main driving-shaft C, which has a bearing in one of the uprights O. 75

Journaled in the frame B is a horizontal shaft, G', extending longitudinally through the tempering-box, and provided with the customary grinding-knives, H'. In the construction and arrangement of these no novelty is herein 80 claimed. The rear end of the shaft G' has a spur-wheel, I', meshing with a pinion, J', upon the main driving-shaft, from which motion is thus transmitted to the said shaft G'. The tempering-chamber is provided with a hopper, K', through which the clay is fed into the 85 machine.

From the foregoing description, taken in connection with the drawings hereto annexed, the operation and advantages of this machine 90 will be readily understood by those skilled in the art to which it appertains. When the machine is in operation, the clay is fed through the hopper into the tempering-chamber, where

100

the spirally-curved knives serve to force it into the tapering pressure-box. The inclined cover of the latter serves to force the clay, with a considerable degree of pressure, in a downward direction into the dies of the mold-wheel, as they pass in succession under the said pressure-box. As the mold-wheel continues its revolution, the plungers are forced upwardly by the inclined track or cam above described, thus expelling the brick, which may then be readily removed.

This machine possesses in a superior degree the advantages of simplicity and ease of operation, and great power is exercised in compressing the clay in the molds or dies. This is due to the relative arrangement of the tempering-chamber, pressure-box, and the mold-wheel.

The general construction and arrangement of parts are simple and efficient, and the machine may be constructed at a less cost than differently-constructed machines of like capacity.

I claim as my invention and desire to se-

cure by Letters Patent of the United States— 25

In a brick-machine, the combination, with the tapering conical horizontal tempering-chamber G, provided with the nose-piece S, and rotary knives for feeding the clay to the discharge, of the mold-wheel arranged horizontally beneath the discharge-opening, provided with molds having bottom flanges to support the plungers, the plungers provided with downwardly-projecting bearings carrying friction-rollers, and a cam-track out of 30 line with the discharge-opening, on which the friction-rollers travel to operate the plungers to expel the brick, and upon which they descend to permit the molds to be filled at the proper time, and mechanism for operating the 35 parts, substantially as specified.

In testimony that I claim the foregoing as my own I have hereto affixed my signature in presence of two witnesses.

PHILIP HENRY KELLS.
